ABRASIVE PROJECTING MACHINE

Chester E. Unger, Mishawaka, Ind., assignor to
 The American Foundry Equipment Company,
 Mishawaka, Ind., a corporation of Delaware

Application June 9, 1938, Serial No. 212,799

13 Claims. (Cl. 51—9)

This invention relates to abrasive projecting machines and more particularly to a rotary centrifugal abrasive machine for throwing abrasive at blasting velocities for cleaning and treating metallic castings, forgings, bars, sheets and like material, which machine embodies means for controlling the direction of flight of the abrasive. In the operation of abrasive projectors of the rotary centrifugal throwing wheel type having one or more throwing blades, in order to obtain control over the direction of flight of the abrasive, it is necessary to deliver the abrasive to the advancing faces of the throwing blades at a predetermined location offset from the axis of rotation of the blades and during their movement through a limited arc. It is desirable that the delivery of the abrasive onto the blades be effected accurately, with a minimum of shock, turbulence, and spillage or leakage of abrasive. In accordance with an illustrative embodiment of the present invention, the machine comprises a rotor having one or more, and preferably a plurality, of throwing blades mounted for rotation. Abrasive is delivered to a rotatable container disposed about the axis of the rotor, and preferably carried by and forming a portion of the rotor, which imparts a rotational velocity to the abrasive. The abrasive is scooped or driven by its rotational velocity over the abrasive guiding edge of a relatively stationary scoop or pick-up member and is discharged from the container. The pick-up member delivers the abrasive in a distributed manner across the inner end portions of the throwing blades and into the path of rotation thereof and at the desired portion of the path of rotation of the throwing blades. The abrasive is urged outwardly along the throwing blades and is hurled therefrom at or near the periphery of the rotor at the desired velocity and in a stream, the direction and shape of which can be controlled by the suitable adjustment of the position of the discharge end of the pick-up member, other factors remaining the same. An object of the invention is the provision of a rotary, centrifugal, throwing wheel having means for delivering abrasive to the throwing blades under directional control and with a minimum of spattering and dispersion.

Still another object of the invention is the provision of a rotary, centrifugal throwing wheel having improved means for delivering abrasive to the throwing blades wherein the abrasive is delivered to the throwing blades at a predetermined location and with a minimum of spillage or leakage and a minimum of grinding of abrasive be-

tween fixed and movable portions of the machine.

Still another object of the invention is the provision of a rotary, centrifugal throwing wheel having directional control means, which wheel is simple and rugged, which is constructed from parts which can be easily and economically formed and assembled, and which can be readily replaced and renewed.

Various other features and advantages of the invention will be apparent from the following particular description and from an inspection of the accompanying drawing.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawing forming a part thereof, in which

Fig. 1 is a front elevational view of one form of apparatus constructed in accordance with the invention, certain of the parts being broken away and other parts sectioned in order to illustrate the interior construction;

Fig. 2 is a transverse cross-sectional view taken along line 2—2 of Fig. 1; and

Fig. 3 is a fragmentary, cross-sectional view of a modified construction.

In the following description and in the claims, various details will be identified by specific names for convenience, but they are intended to be as generic in their application as the art will permit. Like reference characters denote like parts in the several figures of the drawing.

The blasting machine or abrasive projector to which the present invention relates, comprises a machine for hurling granulated material at blasting velocities for the purpose of surface cleaning metal castings, forgings, bars, sheets and like articles. It will be understood that the term "abrasive" may include steel shot, cracked steel grits, quartz sand, and other materials suitable for cleaning castings, forgings, bars and sheets.

The abrasive throwing machine comprises a rotor including a disc or side wall member 1 fixed to a rotatably mounted drive shaft 2, as by a hub 3 secured to the side wall 1, as by bolts 4. The hub 3 is secured against rotation on the shaft 2 as by a pin 5, spline, key or other means.

A plurality of throwing blades 10 are carried on the side wall 1 for rotation therewith. Any suitable number of blades may be employed, but from four to eight blades are usually preferable.

30

35

40

45

50

55

The throwing blades 10 are disposed in spaced and generally radial arrangement and extend from adjacent the periphery of the rotor to inwardly short of the axis of rotation to provide a central space 11. A second side wall member 12 may be provided and is suitably secured to the first side wall member 1 as by studs 14 having reduced ends inserted in the side wall members 1 and 12 respectively. The blades 10 may be suitably secured in place by one or more set screws 15 extending through one of the side wall members and entering the recesses 16 in the blades. Preferably, the throwing blades are formed with side flanges 8 and 9 which seat in suitably positioned grooves 18 and 19 in the inner faces of the side wall members 1 and 12 respectively. In order to facilitate reception of abrasive onto the leading face of the blade, the inner end 7 of each blade preferably is formed as a thinned or tapered lip turned toward the direction of rotation, as indicated.

The rotor is provided with a recess 29 concentrically disposed about the axis of rotation of the rotor. The recess 29 may be defined in any suitable manner and may, if desired, be formed by an integral portion of the side wall member 1 or hub 3 or both. The recess preferably is lined by a circular container or recess member 20. The side wall member 1 is provided with an opening 21 adapted to receive the recess member 20, but if desired, may be provided with a counter-sunk seat to receive the recess member 20. In the illustrative embodiment, the circular recess member 20 extends through the opening 21 and seats in a suitably provided recess 28 in the hub 3.

The recess member 20 is formed to define a recess 29 and is provided with a rear wall 22, peripheral wall 23 and a front wall 24 extending inwardly a limited distance from the periphery to define a front opening 25 and provided with a divergent apron or lip 35. The rear wall 22 may extend over the entire rear of the recess member 20, as illustrated, and thus form a wear plate. It will be noted that the peripheral wall 23 preferably extends over the ends of the grooves 19 and thereby serves to prevent displacement of the throwing blades 10. The recess member 20 is fixed to the rotor for rotation therewith in a suitable manner, as for example, by one or more screws 26 extending through the rear wall 22 and into the hub.

Mounted in relatively fixed position adjacent the rotor, as by a bracket 38, is a generally cone-shaped shield 27 having its inner end surrounding the lip 35. The shield 27 extends out of the space 11 and serves to conduct out of the rotor any abrasive which leaks or spills from the recess member 20 and prevents such abrasive from entering the blades 10.

A feed spout 30 is provided for delivering abrasive to the recess 29 and preferably may be formed with a hopper portion 31 to which abrasive may be delivered in any suitable manner as by a feed conduit (not shown). The feed spout also has a nozzle portion 32 extending through the space 11 defined by the inner ends of the throwing blades 10, through the shield 27 and into the recess member 20. The nozzle portion 32 terminates at a point which preferably is determined by the operating characteristics of the wheel, which, in the present illustrative embodiment, is a point substantially above the lowermost portion of the recess 29, or what may be designated as the "6:00 o'clock" position.

For the purpose of scooping up abrasive from the recess 29 and delivering it onto the inner ends of the rotating throwing blades in a stream distributed over substantially the entire axial width of the throwing face of the blades but between the abrasive retaining flanges 8 and 9 thereof, a pick-up member or channeled scoop 40 is disposed in cooperative relation with the recess 29 and the throwing blades 10. The channeled scoop 40 has its inner or leading end 41 extending into the recess 29 and its outer or trailing end 45 terminating closely adjacent the path of rotation of the inner ends of the blades 10 at a location determined by the direction in which the abrasive is to be thrown by the wheel. The channeled scoop has a channeled or trough-shape cross-section, and in the present embodiment, is formed with an abrasive guiding wall or floor 41 and abrasive guiding side walls 42 and 43. The channeled scoop 40 is so shaped and/or banked that the abrasive is positively guided from the recess to the throwing blades and flows with a minimum of resistance along the scoop. The side walls 42 and 43 preferably do not extend to the inner end of the floor 41 and thus turbulence of abrasive at this point is minimized.

The inner end 44 of the channeled scoop 40 is inclined at an angle to the peripheral wall 23 of the recess 29 and is so spaced therefrom so that the scoop picks up or "skims off" abrasive from that in the recess and positively guides the abrasive to adjacent the path of the blades. The outer end 45 is so shaped and positioned that the abrasive is discharged into the path of the blades at the desired point. The shield 27 is provided with a suitable opening 46 through which the outer end 45 of the scoop extends.

The channeled scoop is of such width at its outer end as to extend substantially over the entire axial width of the abrasive receiving faces but between the abrasive confining flanges 8 and 9 of the blades, as illustrated in Fig. 2, for the purpose of providing even distribution of abrasive over the entire axial width of the abrasive receiving faces of the blades.

The channeled scoop 40 is fixedly supported in any suitable manner and preferably is supported at least in part by the shield 27 and adjustably secured therein, as by a bracket 36. The feed pipe 30 is supported in a suitable manner as by a bracket 37, or other suitable supporting means. Thus, it will be seen that the shield 27, feed pipe 30, and channeled scoop 40 all are rigidly but adjustably fixed in the desired positions relative to the rotor and do not rotate.

The operation of the apparatus is as follows.

The machine is operated by rotating the shaft 2 by means of a suitable source of power (not shown) at a suitable speed thereby to rotate the rotor. For example, where the rotor is approximately 19 inches in diameter, it preferably will be rotated at a speed around 2200 revolutions per minute and thus attain a blade tip velocity of around 10,000 feet per minute or upwards suitable for abrading.

Abraive is delivered to the feed spout 30 in suitable quantity and at suitable velocity by gravity or other feed means (not shown), or by a combination of gravity and other feed means.

The abrasive falls or is forced from the nozzle portion 32 of the feed spout 30 and is delivered into the recess 29 defined by the recess member 20, which member rotates with the rotor and consequently is traveling at the same angular velocity. The abrasive is accelerated and is

urged outwardly by centrifugal force so that it is retained in the recess 29, and is carried around in a circular path by the rotation of the rotor.

The inner end 44 of the channeled scoop 40 scoops up or skims off a substantially uniform, continuous stream of abrasive from that accumulated in the recess 29 and, owing to its velocity, the abrasive is urged along the channeled scoop and is guided out of the recess 29 and discharged across the inner ends of the blades 10 and into the path of the leading faces of the blades 10.

The scoop 40 positively guides the abrasive in a substantially continuous stream to adjacent the path of rotation of the inner ends of the blades and discharges it onto the blades in a stream which may extend substantially over the entire axial width of the throwing faces of the blades and which is relatively uniformly distributed over the width of the throwing faces thereof. The stream of abrasive discharged from the scoop thus does not "cut into" the blades and the tendency to wear grooves or channels in the blades is minimized or entirely eliminated.

The floor 41 of the channeled scoop 40 is so shaped that the centrifugal force on the abrasive prevents the abrasive from falling downwardly away from the scoop and the abrasive thus travels along the scoop until it is discharged into the path of rotation of the blades 10. The outer or trailing end 45 of the channeled scoop 40 is so shaped and positioned that it delivers abrasive into the path of movement of the blades 10 with a velocity outwardly of the rotor and in a sense toward the rotation of the rotor. Thus, the abrasive has an initial velocity in the sense of rotation of the blades and is deposited on the leading faces of the blades with a minimum of shock and is urged along the leading faces of the blades with a minimum of bounding and turbulence.

The abrasive discharged into the path of the blades is deposited on the leading faces of the blades and is urged outwardly along the blades and finally hurled from the blades at or near the periphery of the wheel in a divergent stream, the direction of which can be controlled by suitable adjustment of the clock-dial position of the discharge end of the scoop relative to the path of travel of the blades, other factors remaining the same.

Various modifications may be made in the structure within the scope of the invention. One such modified construction is illustrated in Fig. 3 and comprises a side wall member 101 carrying blades 110 and supported for rotation by a hub 103 on a shaft 102. A recess member 120 is provided which is of greater axial width than the recess member 20, illustrated in Figs. 1 to 3. The recess member 120 is provided with a rear wall 122, peripheral wall 123 and front wall 124, the latter being provided with a lip or apron 135. The recess member 120 is inserted in an opening 121 in the side wall member 101 and seats in a recess 128 in the hub 103.

A shield 127 cooperates with the lip 135 and is adapted to support a channeled scoop 140. A feed spout 130 is provided and suitably supported. The scoop 140 and the feed spout 130 are generally similar to those illustrated in Figs. 1 and 2 but are positioned with their end portions within the recess member 120 offset axially of the rotor sufficiently so that the abrasive is delivered to the recess 129 at its forward position and is picked up at its rear portion.

This form of apparatus is operated in a manner generally similar to that above described, except that the abrasive is delivered to the recess 129 at the forward portion thereof and is carried axially along the recess 129 as well as circumferentially before being picked up. Thus, the abrasive travels in a generally spiral path of one or more turns around the axis of the rotor and of sufficient length to permit the abrasive to be accelerated to the desired angular velocity prior to being picked up by the channeled scoop 140. Preferably, the abrasive is accelerated to an angular velocity approaching or substantially equal to the corresponding portion of the recess member 120, before it is picked up by the channeled scoop.

Where the end of the feed spout is axially displaced from the inner end of the channeled scoop, as in the construction shown in Fig. 3, it is usually preferable to locate the inner end of the channeled scoop axially nearer the blades than is the inner end of the feed spout, thus minimizing the distance the abrasive must travel along the channeled scoop.

The present invention provides abrasive throwing apparatus wherein the abrasive is delivered to the throwing blades at the desired location positively and effectively and the abrasive is given an initial velocity in the sense of rotation of the throwing blades whereby bounding and turbulence of the abrasive on the blade faces and wear of the blade faces is minimized. The construction is such that the abrasive is delivered to the throwing blades smoothly and in a substantially uniform manner over the entire or a substantial portion of the axial width of the throwing faces of the blades thereby providing uniform, substantially even distribution of the abrasive thrown from the blades and providing uniform wear of the leading faces of the blades.

The abrasive is delivered to the recess in the rotor in a smooth, even manner with a minimum of agitation and turbulence and with a minimum of leakage or spillage. The channeled scoop picks up or skims off abrasive in a substantially continuous manner from that in the recess and delivers it in a substantially continuous stream to the blades. Thus, there is a substantially continuous flow of abrasive onto the blades, which results in a desirably uniform wear of the blades. Any abrasive which is agitated by the leading end of the channeled scoop will be forced centrifugally back into the recess and will not be sucked into the path of rotation of the blades to cause a stray stream.

The shield may be disposed relatively close to the adjacent portion of the rotor and thus carry away any abrasive which leaks or spills from the recess and effectively prevent such abrasive from falling into the throwing blades. The channeled scoop terminates closely adjacent the inner ends of the blades and the abrasive is immediately picked up by the leading faces of the throwing blades as it leaves the trailing or outer end of the channeled scoop and thus there is a minimum opportunity of spillage or spattering.

The abrasive is discharged by the scoop into the path of rotation of the throwing blades in a stream, the location and direction of which can be closely and accurately controlled and thus the direction of the stream of abrasive hurled from the wheel accordingly can be accurately and closely controlled. The several portions of the apparatus can be readily adjusted in order to

adjust and control the direction of discharge of the abrasive from the throwing blades.

The several portions of the machine are of such shapes that they can be formed easily and economically and can be readily assembled and disassembled. The parts which are subjected to the most wear can be readily replaced and renewed. The construction is simple and rugged and the wear is minimized by reason of the mode 10 of operation.

While certain novel features of the invention have been disclosed herein, and are pointed out in the annexed claims, it will be understood that various omissions, substitutions and changes may 15 be made by those skilled in the art without departing from the spirit of the invention.

What is claimed is:

1. A machine for throwing abrasive at blasting velocities comprising a rotor having a plurality 20 of throwing blades extending inwardly short of the axis of rotation of said rotor, a container positioned between the inner ends of said throwing blades and rotatable with said throwing blades, said container defining an abrasive-receiving recess in said rotor, means for supplying abrasive to said recess, and means including a relatively fixed, abrasive-feeding device for removing abrasive from the interior of said recess and conducting the abrasive into the path of rotation of 25 said blades, said feeding device including a scraper portion extending into said abrasive-receiving recess for scraping abrasive therefrom, and a delivery portion outside said recess formed with a generally circumferential wall and a side flange, said delivery portion being positioned to deliver abrasive to the leading faces of said blades over a limited portion of their path of rotation.

2. A machine for throwing abrasive at blasting velocities comprising a rotor having a plurality of throwing blades terminating inwardly short of the axis of rotation of the rotor, a container rotatable with said throwing blades and defining an abrasive-receiving recess disposed inwardly from said blades, means for feeding abrasive to said recess, and means including a relatively fixed scoop for guiding abrasive from said recess to said blades, said scoop extending from the interior of said recess outwardly thereof and having a discharge edge at a point closely adjacent the path of rotation of the inner ends of said blades and substantially parallel to the inner ends of said blades.

3. An abrasive throwing machine comprising a rotor having a plurality of blades carried thereon for rotation, means including a rotatable receptacle for imparting rotary movement to abrasive contained therein, means for delivering abrasive to said receptacle, and means including a scoop of channel-shaped cross-section extending from the interior of said receptacle outwardly thereof to a point closely adjacent the path of rotation of the inner portions of said blades for guiding abrasive from said receptacle to said blades and for delivering abrasive to the inner portions of said blades over a limited peripheral distance.

4. Abrasive throwing apparatus comprising a rotor having a plurality of spaced throwing blades extending in a generally radial direction from adjacent the periphery to inwardly short of the axis of rotation of the rotor, a container providing an abrasive-receiving recess disposed about the axis of rotation of said rotor and offset axially from said blades, relatively fixed guide means for transferring abrasive from said con-

tainer to said throwing blades including a portion in said recess and a portion exteriorly of said recess and having a discharge edge disposed at a point adjacent the path of rotation of the inner ends of said blades and substantially parallel to the inner ends of said blades, and means for feeding abrasive to said container.

5. An abrasive throwing machine comprising a rotor including a side wall member, a plurality of spaced throwing blades carried by said side wall member and extending in a generally radial direction from adjacent the periphery inwardly short of the axis of rotation of said rotor, and a receptacle seated in and carried by said side wall member and defining a recess disposed inwardly of said throwing blades, a relatively fixed scoop mounted adjacent said rotor and having one end in said receptacle and the other end terminating in an edge exteriorly of the receptacle and adjacent the path of travel of said blades and substantially parallel to the inner ends of said blades for guiding abrasive from said receptacle to said blades, and means for feeding abrasive into said receptacle.

6. An abrasive throwing machine comprising a rotor having a plurality of throwing blades mounted for rotation, a receptacle carried by said rotor and having a circumferential wall, an inner retaining wall and an outer retaining wall, said walls defining a recess disposed around the axis of said rotor, means for guiding abrasive from said receptacle to said blades including a scoop member having a trough-shaped abrasive guiding wall extending into said receptacle and having its inner end generally parallel to said circumferential wall, and a portion extending out of said receptacle and having its outer end generally parallel to and adjacent the inner ends of said blades, and means for delivering abrasive to said annular receptacle.

7. An abrasive throwing machine comprising a rotor having a plurality of throwing blades mounted for rotation, a receptacle carried by said rotor and having a circumferential wall, an inner retaining wall and an outer retaining wall having an opening therein, said walls defining an annular recess of generally trough-shaped cross-section disposed around the axis of said rotor, means for guiding abrasive from said receptacle to said blades including a guide element projecting through said opening with an inner portion positioned to scrape abrasive from said recess and an outer portion positioned adjacent the path of movement of said blades and formed with a surface extending in a generally circumferential direction to guide abrasive into the path of said blades, means for delivering abrasive to said receptacle including a feed pipe projecting through said opening.

8. An abrasive throwing machine comprising a rotor having a plurality of blades carried thereon for rotation, a receptacle defining a recess in said rotor and including an inturned lip at one side of said recess, means for delivering abrasive to said receptacle, normally stationary shield means cooperating with said lip for limiting the delivery of abrasive onto said blades except a predetermined portion of the path of rotation of said blades, and a normally stationary guide element extending into said recess and having an abrasive guiding surface for guiding abrasive from said recess to a point closely adjacent the path of rotation of said blades.

9. An abrasive throwing machine comprising a rotor having a plurality of throwing blades,

a container providing an abrasive receiving recess in said rotor, means for feeding abrasive to said recess, and means for removing abrasive from said recess and discharging it into the path of rotation of said blades, said last means including a relatively fixed, channeled scoop extending into said recess and disposed with its discharge portion terminating closely adjacent the path of rotation of said blades and substantially parallel to the inner ends of said blades.

10. An abrasive throwing wheel comprising a plurality of spaced throwing blades, means mounting said blades for rotation, means including an abrasive receptacle rotatable with said throwing blades for imparting a rotational velocity to abrasive contained therein, and means including relatively fixed, abrasive-guiding means operative to receive abrasive from said receptacle to direct abrasive in a generally helical path axially and outwardly of said wheel and discharge said abrasive into the path of rotation of said throwing blades over a limited circumferential portion of the path of rotation thereof, said abrasive-guiding means including an abrasive-receiving portion in said recess and a discharge portion outside of said recess and terminating adjacent the path of rotation of the inner ends of said blades.

11. Abrasive throwing apparatus comprising a rotor having a plurality of spaced throwing blades extending in a generally radial direction from adjacent the periphery to inwardly short of the axis of rotation of the rotor to provide a central opening, means including a receptacle disposed about the axis of rotation and having an opening at one end, said receptacle having an inturned lip surrounding said opening, relatively stationary means for guiding abrasive from said recess toward said blades, means for delivering abrasive to said recess, and a relatively stationary shield disposed adjacent and substantially coaxial with said opening and cooperating with said lip for limiting undesired movement of abrasive from said receptacle onto said throwing blades.

15. 12. Abrasive throwing apparatus comprising a rotor having a plurality of spaced throwing blades

extending in a generally radial direction from adjacent the periphery to inwardly short of the axis of rotation of the rotor to provide a central opening, means including a receptacle defining a recess disposed about the axis of rotation, said receptacle having an inturned wall, means including a generally conical shield extending from said inturned wall and through said central opening for guiding away from said blades any abrasive which leaks from said recess, means for 10 guiding abrasive from said recess to said blades, and means for delivering abrasive to said recess.

13. A machine for throwing abrasive at blasting velocities comprising a rotor mounted for high speed rotation and including a side wall member and a plurality of abrasive propelling blades carried by said side wall member and extending from adjacent the periphery inwardly short of the axis of rotation of the rotor to provide a central abrasive-receiving opening, an abrasive-receiving container in said central opening and rotatable with said rotor for accelerating abrasive, a relatively stationary abrasive guide including a flat wall portion disposed in said container in position to scrape abrasive therefrom 20 and guide it in a direction both axially and outwardly of said rotor, and a flat wall portion disposed outside of said container adapted to receive abrasive from said first portion and having an abrasive guiding surface extending generally 25 in the direction of travel of the abrasive propelling blades and an edge portion extending generally parallel to the inner end edges of the abrasive propelling blades in position to deliver abrasive over the inner end edges of said blades 30 at a limited peripheral portion of the path of rotation thereof offset from the axis of rotation of said rotor and with a component of movement in the direction of rotation of said abrasive propelling blades, whereby said abrasive is picked up 35 by the advancing faces of said blades and is propelled therefrom adjacent the periphery of said rotor over a limited arc of the path of rotation, and a feed conduit extending into said container for delivering abrasive thereto.

CHESTER E. UNGER.
